TROPHY CUP

Dorothy K. Allen, Libertyville, Ill., assignor to F. H. Noble & Company, Chicago, Ill., a corporation of Illinois

Filed Dec. 27, 1960, Ser. No. 63,346

Term of patent 14 years

(Cl. D29—23)

FIG. 1 is a front elevational view of a trophy cup showing my new design.

FIG. 2 is a side elevational view thereof;

FIG. 3 is a top plan view thereof; and

FIG. 4 is a cross-sectional view taken along the line 4—4 of FIG. 1.

I claim:

The ornamental design for a trophy cup, substantially as shown.
